CHAIR

John D. Rice, 3226 Lawndale Drive,
Greensboro, N.C. 27408

Filed Apr. 7, 1971, Ser. No. 132,259

Term of patent 14 years

Int. Cl. D6—02

U.S. Cl. D6—71

FIG. 1

FIG. 4

FIG. 2

FIG. 3

FIG. 1 is a perspective view of a chair embodying my design;

FIG. 2 is a side elevational view of the chair of FIG. 1;

FIG. 3 is a front elevational view of the chair of FIG. 1; and

FIG. 4 is a top plan view of the chair of FIG. 3.

The side not shown is a mirror image of the side shown while the back of the chair is conventional.

I claim:

The ornamental design for a chair, as shown and described.
